UNITED STATES PATENT OFFICE.

NELLIE GARDNER HOLLAND, OF BOSTON, MASSACHUSETTS.

SHEET, BLANKET, OR THE LIKE.

1,327,824.

Specification of Letters Patent. Patented Jan. 13, 1920.

Application filed December 12, 1918. Serial No. 266,476.

To all whom it may concern:

Be it known that I, NELLIE GARDNER, HOLLAND, a citizen of the United States, residing at Boston, in the county of Suffolk and State of Massachusetts, have invented 5 certain new and useful Improvements in Sheets, Blankets, or the like, of which the following is a specification.

My invention relates to improvements in 10 sheets, blankets or the like and has for its object to provide means for preventing a sheet, blanket or the like from pulling out from the bottom or down from the top of the mattress, as well as preventing the under 15 sheet from wrinkling or becoming displaced.

Another object is to provide means whereby sheets and blankets are retained in position on a bed so that the bed may be readily and quickly made, which is important in 20 hotels and hospitals especially, where there are a large number of beds.

It is well known that sheets particularly are liable to draw up from the bottom or down from the top of the mattress, also to 25 wrinkle under the body, which produces discomfort and inconvenience, especially to invalids, while blankets are liable to draw up from the bottom and when thus loosened readily fall aside.

30 In the accompanying drawings Figure 1 is an isometric view showing an under sheet in position on a mattress. Fig. 2 is a plan of the lower side of an under sheet. Fig. 3 is an isometric view of the lower side of a 35 mattress with an under sheet in position thereon and the lateral portions in operative position. Fig. 4 is a cross section of the sheet on the line $x-x$, Fig. 2, showing a transverse folded portion or pocket-like receptacle partly open. Fig. 5 is view showing details of a modification.

Latitude is allowed herein as to details, since they may be varied or changed at will without departing from the spirit or scope 45 of my invention.

Corresponding and like parts are referred to in the following description and indicated in all the figures of the drawings by the same reference characters.

50 In the drawings 1 designates a sheet provided at the top 2 and the bottom 3 with a transverse folded portion 4 forming a pocket-like receptacle formed by each end portion of the sheet 1 being folded over on 55 itself and maintained in the same flat, parallel plane as the body of the sheet and

when in its inoperative position in contact therewith throughout its entire length. The sheet 1 is an under sheet, while an upper sheet or a blanket is provided with only 60 one transverse folded portion 4 at the bottom 3. The transverse folded portion 4 is secured on each side, preferably by a tape 5 stitched to the sheet 1 by stitches 5^a, the tape 5 passing around from the upper to the 65 lower side of the sheet 1, or the sides of the folded portion 4 may be secured by stitches 5^a only or other suitable means. The transverse folded portion 4 is sufficiently deep to pass over and under the end 70 of a mattress 6 and to be held securely thereon, while on each side of the sheet 1 and the transverse folded portion 4 are a free lateral portion 7 and an extended folded portion 7^a extending the entire length 75 of the sheet 1 or a blanket, adapted to be folded under the mattress 6 and the transverse folded portion 4 and thereby co-operate with the transverse folded portions 4 on the under sheet 1 in holding the transverse folded portions 4 securely in position 80 on the ends of the mattress 6 and in preventing the sheet 1 from pulling out at the top or bottom, as well as preventing the sheet from wrinkling. The extended folded 85 portions 7^a adjacent to the transverse folded portion 4 are preferably secured on all sides by stitches 5^a, so that there will be no loose parts to catch in the bed spring or to tear when being laundried. However, if 90 so desired, the extended folded portions 7^a may be dispensed with, leaving a recess 7^b, as shown in Fig. 5. It is obvious that quilts can be provided with the same means, but the transverse folded portion 4 in that 95 case would be separate and attached to the quilt.

In use the transverse folded portions 4 of the under sheet 1 are passed over the top and bottom ends of a mattress 6 and thereby 100 the top 2 and bottom 3 of the under sheet 1 are held securely, while the lateral portions 7 and extended folded portions 7^a are then folded under the mattress 6 in the position shown in Fig. 3. The upper sheet having 105 a transverse folded portion 4 at the bottom only is then passed over the bottom end of the mattress 6 and its transverse folded portion 4 over the transverse folded portion 4 of the under sheet 1 thereon and the lateral 110 portions 7 and extended folded portions 7^a are folded under the mattress 6. The

blanket also with a transverse folded portion 4 at the bottom only is then put on, so that its transverse folded portion 4 will pass over the transverse folded portions 4 of the upper and under sheets and its lateral portions 7 and extended folded portions 7^a are folded under as previously described in connection with the upper and under sheets. It is thus evident that the under sheet 1, 10 the upper sheet or the blanket cannot be pulled out at the bottom, while the under sheet 1 cannot in addition be pulled out at the top and in coöperation with the lateral portions 7 and extended folded portions 7^a 15 wrinkling or displacing the under sheet is prevented and, consequently, a perfectly smooth surface is maintained. These features render the sheets and blankets particularly useful in hospitals, making the patients comfortable by preventing wrinkling of the under sheet as well as preventing both the sheets and blankets from pulling out of position, thus relieving the nurses from their usual attention to these details and thereby 20 aiding them in their work. I prefer to use the tapes 5 in forming the sides of the transverse folded portion 4, since they are better than stitches only, especially in preventing tearing during laundrying.

30 I claim:—

1. A sheet, blanket or the like having in either end a folded portion formed of an end portion of the sheet folded over transversely on itself and adapted to be maintained in the same flat, parallel plane as the body of the said sheet and when in its inoperative position in contact therewith throughout its entire length, the folded portion thus formed being adapted to be held in position by securing its sides to the body portion, and free lateral portions extending from and the entire length of the sides of the said sheet.
2. A sheet, blanket or the like having in either end a folded portion formed on an end portion of the sheet folded over transversely on itself and adapted to be main-

tained in the same flat, parallel plane as the body of the said sheet and when in its inoperative position in contact therewith throughout its entire length, the folded portion thus formed being adapted to be held in position by securing its sides to the body portion, and free lateral portions extending from and the entire length of the sides of the said sheet and the sides of the said transverse folded portion, the said lateral portions being adapted to extend under the mattress and under the said transverse folded portions and thus to coöperate therewith in holding the said transverse folded portion securely in position on the mattress and in preventing the said sheet from wrinkling or being displaced.

3. A sheet, blanket or the like having in either end a folded portion formed of an end portion of the sheet folded over transversely on itself and adapted to be maintained in the same flat, parallel plane as the body of the said sheet and when in its inoperative position in contact therewith throughout its entire length, the folded portion thus formed being adapted to be held in position by securing its sides to the body portion, lateral portions extending from and the entire length of the sides of the said sheet adapted to extend under the mattress and to coöperate therewith and the said transverse folded portions in preventing the said sheet from wrinkling or being displaced, and an extended folded portion on each side of the said transverse folded portion having its edges secured by sewing or otherwise, adapted to coöperate with the said transverse folded portion and the lateral portions in holding the sheet securely in position on the mattress.

In testimony whereof I have affixed my signature, in the presence of witnesses.

NELLIE GARDNER HOLLAND.
